MEASURED-SERVICE TELEPHONE SYSTEM.

Application filed August 19, 1924. Serial No. 732,917.

This invention relates to telephone exchange systems in general, and more particularly to such systems wherein connections between telephone lines are completed 5 and registered by means of automatic switching apparatus.

In telephone systems where connections are completed under control of impulses transmitted by a calling subscriber and recorded 10 on a register sender, means are generally provided for preparing to charge the calling subscriber, in the event of the successful completion of a call, immediately after response by the called subscriber.

15 In the case of individual lines terminating in an office each message register is associated with, and is individual to a subscriber's line, and the registering of calls may be accomplished in substantially the same manner as that shown and described in 20 the application of S. B. Williams, Serial No. 596,179, filed October 23, 1922, Patent No. 1,517,331, granted Dec. 2, 1924, wherein each subscriber's line is shown as having access to a group of district selector trunks, by 25 means of coordinate line switches. With each district selector trunk taken for use, there is associated certain mechanism which is operated upon the successful establishment 30 of a connection from a calling line to a called line. This mechanism having been prepared during the establishment of the connection is rendered effective upon the disruption 35 thereof to close an operating circuit for the message register associated with the calling subscriber's line.

In the case of two party lines, that is to say where there are two message registers associated with the same line, it is necessary 40 that some discriminating condition exist when a call is initiated by one or the other of the subscribers served by this line, in order that the proper calling subscriber may be charged upon the completion of a successful call.

One manner of accomplishing this special condition is to place ground potential on the tip conductor of the calling line through the call bell at one of the substations when the subscriber's receiver is off the switchhook. However, the condition might arise wherein 45 the conductors of a party line would be accidentally grounded, thus resulting in the placing of a false condition on the line re-

gardless of which of the two parties had initiated the call. It is necessary, therefore, that some means be provided for detecting this false condition prior to the operation of the message register in order to forestall a false charging of the call. 55

It is an object of this invention, therefore, to provide for the proper registering of calls initiated on party lines. 60

This object is obtained by providing a special party test relay associated with each 65 district selector taken for use. This test relay is, during the establishment of a connection, first energized over a local circuit and at a later stage in the progress of the connection this same test relay in its operated 70 condition is applied to the conductors of the calling line to test for the presence or absence of a discriminating condition thereon. Should party No. 2 have initiated the call, a discriminating ground will be found 75 upon the line and the test relay will remain energized for an interval (as determined by a time measuring mechanism) to operate a party recording relay, after which the test relay is again released. Should the test relay 80 remain operated longer than the period determined by the time measuring mechanism, a signal is given to an attendant. Prior to the disconnection of the test relay from the calling line a check is made of the operating 85 characteristics thereof as will be described in detail hereinafter.

Should, however, party No. 1 have initiated the call no discriminating ground would 90 be found upon the tip conductor of the calling line when the test relay is applied thereto. Consequently before the time measure mechanism has completely functioned the test relay is released and the party recording relay remains normal. When party No. 2 95 initiates the call the recording relay associated with the district selector remains operated until disruption of the connection in order to determine the operation of the proper message register. 100

A feature of the invention relates to an improved means for determining a standard or unstandard condition of a calling line for the purpose of correctly registering the calls initiated thereon. 105

A further feature of the invention relates to a party test relay which is applied to the calling line in an operated condition to de-

termine the presence or absence of unstandard conditions and also for the purpose of responding to a discriminating condition on said calling line.

5 While it has been chosen to illustrate the invention as applied to a telephone system wherein switches of the coordinate type are employed, it is understood that the invention in its broad aspects is not to be confined to 10 this particular kind of system since it may be equally well applied to so-called power drive systems and in general to any system wherein selective operation of party line message registers is required.

15 The invention is an improvement on the call charging system disclosed in the application of D. M. Taggart and F. J. Scudder Serial No. 431,141, filed December 16, 1920, Patent No. 1,513,351, granted Oct. 28, 1924, 20 wherein switches of the power driven type are shown. The invention disclosed herein however, is shown as applied to a telephone system of the general character disclosed in the application of S. B. Williams Serial No. 25 596,179, filed October 23, 1922, Patent No. 1,517,331, to which reference may be had for a detailed description of the construction and operation of the several switches and controlling mechanisms shown in the drawings.

30 Figs. 1, 2 and 3 of the drawing when arranged with Fig. 2 to the right of Fig. 1, and Fig. 3 to the right of Fig. 2 show, partly in schematic form and partly in detail, sufficient portions of a telephone system embodying the features of the invention to enable one to obtain a complete understanding thereof.

Fig. 1 shows one of a number of telephone lines accommodating two subscribers' substations. To the right of Fig. 1 is also shown a 40 line switch of the coordinate type. The portion of this figure included in the rectangle is intended to represent a master switch for controlling the selective operation of the line switch. In the lower left hand portion of this figure are shown two subscribers' stations with the usual telephone apparatus associated with automatic substations.

Fig. 2 shows one of a number of district 50 selector trunks and associated controlling mechanism.

Fig. 3 in the lower left portion shows in schematic form a coordinate sender selector switch by means of which calling lines are 55 associated with idle register senders. In the lower portion of this figure are also shown schematically a number of markers or switch controlling mechanisms together with various connecting devices. In the upper portion of this figure are shown diagrammatically a district switch, a local incoming switch and a final or connector switch.

The line switch 100, sender selector switch 350, district selector switch 380, incoming 60 switch 390 and final switch 395 may be of the

general type disclosed in the application of S. B. Williams, Serial No. 596,179, filed October 23, 1922, Patent No. 1,517,331. These switches consist in the main of a plurality of horizontal link circuits, and a plurality of sets of vertically and horizontally disposed operating members. The horizontal operating members are each individual to a link circuit, and the vertical operating members are apportioned amongst incoming lines and outgoing trunks. The selective operation of a pair of vertical operating members and a particular horizontal operating member determine the selective operation of the switch. Furthermore, the structure of the switch is of such a nature that a plurality of connections from lines to trunks may coexist there-through.

The sender 310 is of the well known type, comprising relay registers for recording sets of impulses as determined by the operation of a calling subscriber's dial, together with certain controlling equipment for automatically supervising the establishment of connections from calling lines to called lines.

The markers or switch controlling mechanisms 320 and 330 are accessible in common to a number of senders as 310. These markers serve to receive certain information from a register sender to which they are attached in sequence to subsequently control the operation of the several selective switches, such as the district, incoming and final switches to complete the extension of a calling line to a particular called line. When these respective controlling operations have been completed the markers and the sender are discharged and revert to common use.

Detailed description.

It will be assumed for the purpose of description that the subscriber at station 102 has initiated a call with the purpose of conversing with the subscriber at station 315 whose line is located in the same exchange with that of the calling subscriber. The removal of the receiver by the calling subscriber causes line switch 100 to automatically operate to extend the line 110 to an idle district trunk, such as trunk 150, leading to a district selector switch 380. The connection of line 110 with trunk 150 is accomplished by first causing the operation of the magnet 112 associated with the vertical row of contacts 121. The operation of magnet 112 is immediately followed by the operation of a magnet such as 113, 114, etc., associated with the first idle outgoing trunk. Assuming that trunk 150 is the first idle trunk then magnet 113 individual thereto is operated. With magnets 112 and 113 operated a circuit is closed for a horizontal magnet, as magnet 115, associated with the first idle link, as link 116, accommodating line 110 and giving access to trunk 150.

When magnet 115 operates, connection of line 110 with trunk 150 is completed and vertical magnets 112 and 113 begin to release. When these magnets have released, connection of line 110 with trunk 150 through link 116, is maintained, since magnet 115 is now held energized through both its windings in series to the grounded sleeve conductor of trunk 150. The sleeve conductor of trunk 150 is temporarily grounded when magnet 113 operates. This ground is also extended by means of the sleeve conductor of trunk 150, conductor 254, upper inner and lower inner contacts of relay 203, lower inner armature and back contact of relay 205, conductor 255, to battery through the winding of relay 301, associated with sender selector switch 350. In the manner described in detail in the above mentioned application of S. B. Williams, Serial No. 596,179, filed October 23, 1922, Patent No. 1,517,331, the operation of relay 301 causes switch 350 to automatically operate to associate an idle register sender, as 310, with trunk 150 by means of the group of conductors 351.

When sender selector switch 350 has operated and a sender has been selected, ground is extended over holding conductor 352 to battery through the left winding of relay 213. The operation of relay 213 at its left outer armature extends this same ground through the winding of relay 201 which operates. Relay 201 connects ground through its lower outer armature and front contact thence through the upper normal contacts of relay 206 and the lower outer contacts of relay 203, winding of relay 207, to battery through the lower left winding of repeating coil 256. Relay 207 operates in that circuit. Relay 201 connects ground through its upper outer armature and front contact to battery through the winding of relay 205 which operates. Relay 205 completes a locking circuit through its winding and locking contact, lower inner contacts of relay 203 to ground at the upper inner contacts of relay 205. This holding circuit for relay 205 is maintained until the disruption of the connection. Relay 205 connects ground through its upper inner contacts to the sleeve conductor of trunk 150. By means of the left outer contacts of relay 211 this ground serves to replace the ground which was temporarily applied when magnet 113 operated. It will be observed that there is associated with the line switch 100 a master control switch 160 (shown diagrammatically). The operation of this master switch is described in detail in the patent to S. B. Williams, hereinbefore referred to, and is of such a nature as to allow an appreciable interval between the operation and release of magnet 113. This interval is of sufficient duration to permit the preceding described operations to take place. Consequently when relay 205

operates and places holding ground on trunk 150, magnet 115 is maintained energized to preserve the connection through switch 100.

With relays 205 and 213 operated the circuit above traced for energizing start relay 301 is now broken and this relay releases. The connection through switch 350 is maintained, however, by the continued energization of a magnet such as 303 which is locked through both windings in series, through contacts of switch 350 to holding ground supplied by the sender 310.

With relay 213 operated a circuit is completed from battery at the left inner contacts of relay 212 thence through the winding of relay 210, lower outer normal contacts of relay 202, resistance 257 to ground at the left inner contacts of relay 213. Relay 210 operates and closes an obvious circuit for relay 215 which also operates. When interrupter 251 closes its upper contacts subsequent to the operation of relay 213 battery is connected through the left outer armature and back contact of relay 212, normal contacts and winding of relay 206, resistance 258, to ground at the armature of relay 213. Relay 206 operates in this circuit and immediately closes a locking circuit for itself traceable from battery at the left inner contacts of relay 212, locking contact and winding of relay 206 to ground at the armature of relay 213. Relay 206, by opening its upper normal contacts, breaks the above traced circuit for operating relay 207 and this relay releases. A short interval later, when interrupter 251 closes its lower contacts, battery is connected through the lower inner normal contacts and winding of relay 202 to ground at the upper inner contacts of relay 206. Relay 202 locks in a circuit traceable from battery at the left inner contacts of relay 212, locking contact and winding of relay 202 to ground at the armature of relay 206. A holding circuit for the test relay 210 is now completed from ground through resistance 259, lower outer contacts of relay 201, lower outer contacts of relay 202, winding of relay 210 to battery at the contacts of relay 212. Test relay 210 under normal conditions is maintained energized in this circuit so long as relay 201 is operated and the sender 310 is attached to the calling line.

When relay 201 operated the tip and ring conductors of the extended calling line were transferred through contacts of relay 201 and switch 350 to the impulse relay in sender 310. The calling subscriber next interrupts the line circuit in accordance with the designation of the wanted line. The impulse relay in the sender follows these interruptions and causes the called line designation to be recorded on the sender registers. In the manner described in detail in the above mentioned application of S. B. Williams,

Serial No. 596,179, filed October 23, 1922, Patent No. 1,517,331, the record of the office designation is transferred from the sender registers to corresponding registers in the outgoing marker 320, wherein this transferred record is thereupon translated to identify a group of trunks, including trunk 355, leading from district switch 380 to incoming switch 390. The connector device 360 having been operated after sender selector 350 was actuated identifies the particular district switch 380 in which trunk 150 terminates. The connecting device 370 is now selectively operated in accordance with the translated office record in marker 320. With connectors 360 and 370 operated the testing equipment in marker 320 is associated with the links in switch 380 and with the trunks in the group including trunk 355. It will be assumed that link 354 and trunk 355 constitute the first available path for extending the calling line through switch 380. The marker now proceeds to operate the horizontal magnet 356 associated with link 354, the vertical magnet 364 associated with vertical row of contacts 358 having previously operated. Vertical magnet 359 was operated prior to the operation of frame connector 360. With vertical magnets 357, 364 and horizontal magnet 356 operated, trunk 150 is connected by means of link 354 to trunk 355. The outgoing marker 320 having completed its function in controlling the operation of switch 380 is discharged, causing the release of connectors 360 and 370 and sender connector 365. The release of these connectors in turn causes the restoration to normal of magnets 359 and 364. The connection through link 354 is now maintained by magnet 356 which is held energized through both its windings in series and thence through contacts of switch 380 to the grounded sleeve conductor of trunk 150. For a detailed description of the manner in which the marker controls the operation of switch 380 reference may be had to the above mentioned application of S. B. Williams, Serial No. 596,179, filed October 23, 1922, Patent No. 1,517,331, and also to Patent No. 1,600,399, granted September 21, 1926, to W. W. Carpenter.

When magnet 359 operated, conductor 361 which was grounded by the marker, was extended through an armature of magnet 359 to conductor 363, and thence to battery through the right winding of relay 214. Relay 214 immediately locks in a circuit traceable from battery through its left winding and locking contact to ground at the upper inner contacts of relay 206. This same ground is now extended by means of the locking contact of relay 214, conductor 262, resistance 263, upper outer contacts of relay 206, lower outer armature and back contact of relay 203, winding of relay 207 to bat-

tery through the lower left winding of repeating coil 256. Relay 207 is operated at this time to break the circuit which extends through the left winding of relay 212, the left outer armature and back contact of relay 209, contacts of relay 207, upper middle contacts of relay 205 and thence to the upper outer back contact of relay 201, so that when relay 201 releases upon the completion of the connection as hereinafter described, relay 212 will not operate.

When connection was completed through switch 380 as hereinbefore described, and marker 320 was released, the connecting device 375 was operated to associate the sender with an idle incoming marker 330. When a marker has been thus associated the numerical portion of the called line designation is transferred from the sender registers to corresponding registers in marker 330 wherein this record is thereupon translated and results in the selective operation of incoming switch 390 and final switch 395, whereby an idle link in switch 390, before which trunk 355 appears, is selected, and in addition an idle link in switch 395 giving access to the called line 315 is also selected. At the same time an idle trunk is selected extending between switches 390 and 395 and appearing before the group of links in switch 395 giving access to the called line 315. The application of S. B. Williams, E. S. Gibson, Serial No. 722,215, filed June 25, 1924, Patent No. 1,600,444, granted Sept. 21, 1926, described in detail the manner in which the marker 330 is associated with the register sender and also the manner in which the various connecting devices 371, 372, 373 are selectively operated to control the selective operation of incoming and final switches to complete connections to called lines. Inasmuch as the present invention is concerned mainly with the manner in which message registers are selectively operated, it is believed not to be necessary to give a detailed description of the operations of the connecting devices 371, 372, etc., and switches 390, and 395 which therefore have been described in a general manner.

When connection has been completed with the called line, which it will be assumed is idle, the sender selector, the sender and marker are thereupon discharged and revert to common use. When the sender releases holding ground is removed from conductor 352 causing the release of the sender selector and relays 201 and 213. With relay 201 released test relay 210 is connected in its operated condition to the tip side of the calling line by means of the upper inner armature and front contact of relay 202 and the upper inner armature and a back contact of relay 201, thence through contacts of switch 100 to the tip conductor of line 110, through

contacts engaged by the calling subscriber's switchhook to ground through the ringer coils 105. A parallel circuit also extends through the lower contact of relay 202 to the ring side of the line. Relay 201 is so adjusted that upon deenergization thereof the upper inner armature and back contact close, before the lower outer armature and front contact disengage. Test relay 210 is thus maintained energized by the ground at station 102. It will be noted that if the party at station 101 had initiated the call, ringer ground would be disconnected from the tip conductor of trunk 150 by means 15 of condenser 107. Thus when relay 201 releases after seizure of the called line it would bring about the release of relay 210 providing no unstandard conditions exist upon the extended calling line.

20 Test relay 210 having been applied to the calling line in an operated condition and the discriminating ground having been encountered relay 210 remains operated after relay 201 releases. Relay 210 in turn maintains relay 215 energized. When interrupter 252 closes next its left contacts battery is connected through the right normal contacts and right winding of relay 208, thence through the upper outer armature 25 and front contact of relay 202 to ground at the armature of relay 201. Relay 208 locks in a circuit traceable from battery at the left inner contact of relay 212, locking contact and right winding of relay 208 to the above 30 traced ground at the armature of relay 201.

35 When interrupter 252 closes its right contacts relays 216 and 213 operate. The circuit for operating relay 213 may be traced from battery through the right contacts of interrupter 252, right outer contacts of relay 208, right normal contacts and right winding of relay 213, conductor 264, upper outer armature and front contact of relay 202, to ground at the armature of relay 201. The circuit for operating relay 216 may be traced from battery through the right contacts of interrupter 252, right outer contacts of relay 208, right outer armature and front contact of relay 215, right winding of relay 216 to ground as above traced at the armature of relay 201. Relay 213 locks in a circuit traceable from battery at the left inner contacts of relay 212, locking contact and right winding of relay 213 to ground as above traced. A locking circuit is also completed for recording relay 216 which may be traced from battery through the left winding and locking contact thereof, left outer contacts 50 of relay 211 to ground through the upper inner contacts of relay 205. Relay 216 operates to record the fact that the second party on line 110 has initiated a call.

55 The circuits remain in this condition until interrupter 252 again closes its left contacts

whereupon battery is connected through the left contacts of said interrupter, right inner contacts of relay 209, right outer contacts of relay 213 and thence to one terminal of the winding of relay 206; the other terminal of relay 206, also being connected to battery, this relay is now shunted and releases.

60 Relay 206 in turn causes the release of relay 202, the latter relay upon its release opening the previously traced operating circuit for test relay 210. The above traced circuits for operating relay 210 it will be remembered were closed through the armatures and front contacts of relay 202. When therefore relay 202 releases as described a 65 substitute circuit is completed for relay 210 which may be traced from battery, at the left inner contacts of relay 212, winding of relay 210, lower normal contacts of relay 202, left outer armature and front contact of relay 215, high resistance 265 to ground. Resistance 265 is of such a value as to correspond to the maximum allowable line leakage. Relay 210 is so adjusted mechanically and electrically as to be normally unable to 70 remain energized when its winding is included in series with resistance 265. Should therefore relay 210 remain operated when connected in series with resistance 265 it is 75 an indication that relay 210 is not correctly 80 adjusted.

85 Furthermore if relay 210 should remain operated in series with resistance 265 ground is connected through the upper outer armature and back contact of relay 201, conductor 266, left inner contacts of relay 215 and thence to conductor 267. Conductor 267 leads to a selector time alarm circuit 90 95 299 and the presence of ground on this conductor causes this alarm to function. At 100 the end of a predetermined interval the continuance of this ground condition on conductor 267 causes an alarm signal to be operated at an attendant's position who can 105 ascertain the nature of the trouble.

110 It will be assumed, however, that test relay 210 is correctly adjusted and therefore releases when included in series with resistance 265 upon the release of relay 202. When relay 206 releases it opens the locking 115 circuit of relay 214, and when relay 202 releases it opens the locking circuit of relay 213. Relays 213 and 214 are now in their normal condition. When relay 202 releases it also opens the locking circuit of the slow 120 releasing time measure relay 208 which also begins to release. Supervisory relay 207 is now held in a circuit traceable from battery through the lower left winding of repeating coil 256, winding of relay 207, lowermost armature and back contact of relay 203, upper normal contacts of relay 206, lower normal contacts of relay 201, thence over the ring side of trunk 150, through contacts of switch 100, ring conductor of the calling line 125 130

through the calling subscriber's substation apparatus, returning thence over the tip side of the calling line through contacts of switch 100, to the tip conductor of trunk 150. 5 thence through the upper inner armature and back contacts of relays 201 and 202, upper outer armature and back contact of relay 203 to ground through the upper left winding of repeating coil 256. The connection is 10 now in a stable condition awaiting the removal of the receiver by the called subscriber.

When the called subscriber removes the receiver from the switchhook the direction 15 of the current in trunks 355 and 150 is reversed causing the operation of the polarized relay 204. For the manner in which response by the called subscriber causes the reversal of the direction of the current to 20 operate relay 204 reference may be had to the application of S. B. Williams, Serial No. 596,179, filed October 23, 1922, Patent No. 1,517,331, above referred to.

When interrupter 253 closes its right contacts subsequent to the operation of relay 204, battery is connected through the left normal contacts and left winding of relay 208, lower contact and armature of relay 204 to ground. Relay 208 closes a locking 25 circuit for itself which may be traced from battery, at the left normal contacts of relay 209, left locking contact and left winding of relay 208, to ground as above traced. A short interval later when interrupter 253 30 closes its left contacts, battery is connected through the left outer contacts of relay 208, right winding of charging relay 209, to ground through the upper outer armature and back contacts of relays 202 and 201. 35 Relay 209 in attracting its left inner armature opens the previously traced locking circuit for relay 208 which becomes deenergized. Relay 209 is now locked in a circuit 40 traceable from battery through its locking contact and left winding and thence to ground on the sleeve conductor of trunk 150. The district trunk and associated apparatus 45 remain in this condition until the termination of conversation.

50 When the calling and called subscribers have replaced their receivers upon their respective switchhooks, relays 204 and 207 release. The release of relay 204 connects ground through its armature and upper 55 contact, thence through the right middle contacts of relay 209 to conductor 267 which leads to the selector time alarm circuit hereinbefore referred to. The purpose of operating the selector time alarm at this time 60 is to prevent the calling subscriber from maintaining a connection in its busy condition for an indefinite interval subsequent to disconnection by the called subscriber. Upon the release of relay 207 a circuit is also 65 completed from battery at the left inner

contacts of relay 212, winding of relay 210, lower outer normal contacts of relay 202, resistance 257, left outer armatures and front contacts of relays 216 and 209, armature and back contact of relay 207, 70 through the upper middle armature and front contact of relay 205, to ground at the armature of relay 201. Relay 210 operates in this circuit. When interrupter 251 75 closes its upper contacts subsequent to the release of relay 207 battery is connected through the left outer armature and back contact of relay 212, thence through the normal contacts and winding of relay 206, conductor 268, resistance 258, left outer armature and front contacts of relays 216 and 209, armature and back contact of relay 207, upper middle contact of relay 205 to ground at the armature of relay 201. The purpose of operating relay 206 at this time 85 is to make a check test of the calling line to determine the presence or absence of unstandard conditions thereon. When interrupter 251 next closes its lower contacts 90 battery is connected by means of conductor 269 through the lower inner normal contacts and winding of relay 202 and thence to ground at the upper inner contacts of relay 206.

With relay 202 operated, test relay 210 is 95 connected in its operated condition, by means of the lower outer armature and front contact of relay 202, to the ring conductor of trunk 150 and thence by means of contacts in switch 100 to the ring conductor of the calling line. In parallel with this circuit another circuit is traceable 100 through the upper inner armature and front contact of relay 202 to the tip conductor of trunk 150 and thence to the tip conductor 105 of the calling line. Since the calling subscriber has replaced his receiver and thus disconnected ground from the tip conductor of the line, should an unstandard condition prevail thereon, such as a false ground or 110 a line leakage greater than that allowable, ground will be extended to maintain test relay 210 in its operated condition. Relay 210 115 remains energized also holding relay 215 in its operated condition. Thus relays 210, 202 and 206 remain operated as a result of the unstandard condition on the calling line. Under these conditions grounds is connected by means of the upper outer armature and back contact of relay 201, and thence 120 through the left inner contacts of relay 215 to conductor 267 which leads to and causes the selector time alarm circuit to function as hereinbefore described.

Should relay 210 release when it is connected to the tip and ring conductors of the extended calling line as a result of the operation of relay 202, it is an indication 125 that no false ground or unstandard condition exists on the line and that relay 210 130

operated correctly in accordance with the discriminating ground as previously described. The release of relay 210 under these conditions causes the release of relay 215. The circuits remain in this condition until interrupter 252 closes its left contacts, whereupon battery is connected through the right normal contacts and right winding of relay 208, thence through the upper outer armature and front contact of relay 202 to ground at the armature of relay 201. Relay 208 operates in this circuit and closes a locking circuit for itself as previously traced. When interrupter 252 next closes its right contacts, battery is connected through the right outer contacts of relay 208, thence through the right outer armature and back contact of relay 215, the right inner contacts of relay 216, through the right winding of relay 212 to ground. Relay 212 operates in this circuit and closes a locking circuit for itself which may be traced from battery, through its left winding thence through the right middle contacts of relay 212, armature and back contact of relay 207, upper middle armature and front contact of relay 205, to ground at the armature of relay 201.

The operation of relay 212 at this time by removing battery from the left inner contact of said relay opens the previously traced holding circuits for relays 202 and 206 and these relays now release. In addition relay 212 by means of its right outer contacts connects ground to the sleeve conductor of trunk 150 to replace the holding ground which is later to be removed when relay 205 releases. When interrupter 251 closes its upper contact, battery is connected through the left armature and front contact of relay 212, thence through the normal contact and right winding of relay 211, contacts of relay 207, to ground through the upper middle contacts of relay 205 as previously traced. Relay 211 operates in this circuit and immediately closes a locking circuit for itself which is traceable from battery, through the locking contact and right winding of relay 211 to ground as above traced. When interrupter 251 next closes its lower contacts, battery is connected by means of conductor 269, through the right outer contacts of relay 211, thence through the left inner contacts of relay 211, to ground through the lower winding of relay 203. The operation of relay 203 opens the previously described locking circuit of holding relay 205 and this relay releases, removing ground from conductor 357 thus causing release of switches 380 and 390. Holding ground is, however, maintained on the sleeve conductor of trunk 150 by means of relay 212 which remains locked so long as interrupter 251 maintains its lower contacts in a closed condition. With relay 205 normal and interrupter 251 main-

taining its lower contacts closed battery is connected by means of conductor 269, through the right outer contacts of relay 211, thence to conductor 271, through the lowermost contacts of relay 205, resistance 272, right outer contacts of relay 209, right outer armature and front contact of relay 216, conductor 273, thence through contacts of switch 100 to conductor 163 to ground through the winding of message register 103 which is associated with substation 102. Message register 103 operates in this circuit and causes the call to be recorded.

After a short interval when interrupter 251 opens its lower contacts, battery for maintaining relays 211 and 212 operated is disconnected and these relays release. The release of relay 212 removes holding ground from the sleeve conductor of trunk 150 thus bringing about the release of horizontal magnet 115 in the line switch. For a detailed description of the manner in which the removal of ground from the district trunk causes the release of the selector switches, reference may be had to the patent to S. B. Williams, No. 1,517,331, hereinbefore referred to.

Should the first party, that is the party at station 101, have initiated the call then ringer ground would be missing from the line conductors of the line when the original party test was made, and relay 216 would remain normal. In this case after disconnection by the calling party no check test is necessary to determine the absence of ground on the tip and ring conductors of the extended line. Since relay 216 is normal when interrupter 251 closes its upper contact subsequent to the release of relay 207, the circuit hereinbefore traced for relay 206 is opened at the outer left contact of relay 216. Consequently neither relay 202 nor relay 215 operate to perform the check test as above described.

Under these conditions as soon as relay 207 releases following disconnection by the calling party, a circuit is immediately closed for relay 212 which may be traced from battery through the left winding of relay 212, normal contacts of relay 216, left outer armature and front contact of relay 209, contacts of relay 207, upper middle contact of relay 205 to ground at the armature of relay 201. When interrupter 251 closes its upper contact subsequent to the release of relay 207 the circuit hereinbefore described for operating relay 211 is closed and this relay is energized. A short interval later when interrupter 251 closes its lower contact, relay 203 is operated as previously described. Relay 203 in turn causes the release of holding relay 205. When relay 205 releases a circuit is completed for operating the message register associated with substation 101. This circuit may be traced from battery through the

lower contacts of interrupter 251, conductor 269, right outer contacts of relay 211, conductor 271, lowermost contacts of relay 205, resistance 272, right outer contacts of relay 209, right outer armature and back contact of relay 216, conductor 274, and thence through contacts of switch 100 to conductor 164 to ground through the winding of message register 104. When interrupter 251, 5 a short interval later, opens its lower contact, relays 212 and 211 release and cause the restoration of the circuit and the selector switches to normal as previously mentioned.

Should the called party fail to answer 15 when the bell at substation 315 is rung, relay 204 fails to operate. Since relay 204 is normal when interrupter 253 closes its right contact the circuit previously described for operating relay 208 is opened and relay 208 fails to operate. When interrupter 253 20 closes its left contact no operating circuit is found for charging relay 209 and this relay remains normal, thus preventing the operation of the message register since the 25 operating circuit for the message register is opened at the right outer contacts of relay 209. In this case also no check test of the calling line is performed, since no registration is necessary. Consequently, when relay 207 releases following the replacement 30 of the receiver by the calling subscriber, the above-traced circuit for operating relay 210 is opened at the left outer contacts of relay 209 which remains normal when the called 35 subscriber fails to answer. Immediately that relay 207 releases, the circuit for operating relay 212 is closed from battery through the left winding of relay 212, left outer armature and back contact of relay 209, to ground through contacts of relays 40 207, 205 and 201. When interrupter 251 closes its upper contacts subsequent to operation of relay 212, the above traced circuit is closed for operating relay 211, and when 45 interrupter 251 closes its lower contacts the above traced circuit is closed for operating relay 203, which causes release of relay 205 and the consequent restoration to normal of the various pieces of apparatus employed in 50 the connection.

What is claimed is:

1. In a telephone exchange system, a calling line, a plurality of subscribers' stations on said line, a called line, automatic switching mechanism for extending said calling line to said called line to establish a conversational connection, message registers associated with said calling line and each individual to a subscriber's station, means associated with said subscribers' stations for placing discriminating test conditions on said calling line, a testing means associated with certain of said automatic switches, said testing means being normally disconnected 55 from the extended calling line, means for

operating said testing means, means for applying said testing means in its operated condition to the extended calling line, and means responsive to the presence of a test condition for causing said testing means to 70 select the message register individual to the calling station.

2. In a telephone exchange system, a calling line, a plurality of subscribers' stations on said line, a called line, automatic switching mechanism for extending said calling line to said called line to establish a conversational connection, message registers associated with said calling line and each individual to a subscriber's station, means associated with said subscribers' stations for placing discriminating test conditions on 75 said calling line, a testing relay associated with one of said automatic switches, said testing relay being normally disconnected from the extended calling line, means for operating said testing relay, means for applying said testing relay in its operated condition to the extended calling line, means responsive to the presence of a particular 80 test condition for causing said testing relay to select the message register individual to the calling station, and means effective after the successful completion of a conversational 85 connection for operating the selected message register.

3. In a telephone exchange system, a calling line, a plurality of subscribers' stations on said line, a called line, an automatic switch, a series of selective switches for completing conversational connections between said calling line and said called line, a group of trunks leading from said automatic switch to the first switch in said series, a message register individual to each station, 90 individual operating circuits for said message registers extending through contacts of said automatic switch, a plurality of testing means each individual to a trunk in said group of trunks and normally disconnected 95 therefrom, means responsive to the initiation of a call at any of said stations for operating said automatic switch to seize an idle 100 trunk in said group to extend the calling line to said series of selective switches, 105 means associated with said stations for placing discriminating test conditions on said calling line, means effective subsequent to the seizure of said one of said trunks for operating the testing means individual thereto, 110 means for applying said testing means in its operated condition to the extended calling line, means responsive to the existence of one of said test conditions for causing said testing means to select the register operating 115 circuit individual to the calling station, and means effective after the successful completion of a conversational connection for rendering said selected operating circuit effective.

4. In a telephone exchange system, a calling line, a plurality of substations on said line, a called line, a line switch, a series of selective switches for establishing conversational connections between said calling line and said called line, a group of trunks leading from said line switch to the first switch in said series, a message register for each substation, individual operating circuits for 5 said message registers extending through contacts of said line switch, a plurality of testing means each individual to a trunk in said group of trunks and normally disconnected therefrom, means responsive to the initiation of a call at any of said stations for operating said automatic switch to seize an idle trunk in said group to extend the calling line to said series of selective switches, means at one only of said substations for placing a discriminating ground potential on one of the calling line conductors, means effective upon the seizure of said one of said trunks for locally operating testing means individual thereto, means for connecting said testing means in its operated condition to the extended calling line, means responsive to the existence of said ground potential on said conductor for causing said testing means to select the register operating 10 circuit individual to the calling substation, and means effective after the successful completion of a conversational connection for rendering said selected operating circuit effective.
5. In a telephone exchange system, a calling line, two subscribers' stations on said line, a called line, an automatic switch, a series of selective switches for completing conversational connections between said calling line and said called line, a group of trunks extending between said automatic switch and said series of selective switches, means at one of said stations for placing a discriminating ground potential upon the conductors of said calling line, message registers associated with said calling line and each individual to a subscriber's station, an operating circuit for said registers normally arranged for association with one of said 15 registers, switching means for associating said operating circuit with the other of said registers, a plurality of testing means each individual to a trunk in said group of trunks and normally disconnected therefrom, means responsive to the initiation of a call at either of said stations for operating said automatic switch to extend the calling line to an idle trunk in said group, means effective subsequent to the seizure of said idle trunk 20 for locally operating the testing means individual thereto, means for connecting said testing means in its operated condition to the extended calling line, means responsive to said connection of said testing means and the existence on the calling line of said dis-
- criminating potential for operating said switching means, and means effective after the successful completion of a conversational connection for operating said other of said message registers. 70
6. In a telephone exchange system, a calling line, two subscribers' stations on said line, a called line, means for extending said calling line to said called line to establish a conversational connection, message registers 75 associated with the incoming end of said calling line and each individual to a subscriber's station, means at one of said stations for placing a discriminating test condition upon one conductor of the calling line, testing means normally disconnected from said extended calling line, means for operating said testing means while disconnected from the extended calling line, means for subsequently applying said testing means in its operated condition to the extended calling line, means responsive to said application of said testing means and to the existence of said test condition or an unstandard 80 condition on the extended calling line for 85 selecting one of said message registers, means operative upon the successful completion of a conversational connection for preparing the selected message register for operation, and means effective upon the release 90 of the connection and effective only when said line is in a standard condition for operating said selected message register. 95
7. In a telephone exchange system, a calling line, two subscribers' stations on said line, a called line, automatic switches for extending said calling line to said called line to establish a conversational connection, message registers associated with said calling line and each individual to a subscriber's station, means at one of said stations for placing a discriminating ground test condition upon the conductors of the calling line when a call is initiated at such station, a testing means associated with certain of said 100 automatic switches responsive to said test condition for causing the selection of the message register corresponding to the calling station, said testing means being normally disconnected from the extended calling line, means responsive to a partial extension of the calling line for locally operating said testing means, connecting means operative 105 prior to the complete extension of the calling line for connecting said testing means in its operated condition to said conductor of said calling line to detect thereon the presence of said test condition or an unstandard 110 ground condition, means operative upon the successful complete extension of the calling line to the called line for preparing the selected register for operation, means effective upon the restoration of the calling subscriber's receiver to its switchhook for reoperating said testing means and for recon- 115 120 125 130

necting the same in its operated condition with said calling line to detect the existence thereon of an unstandard condition, and means operative thereafter for operating 5 said selected message register only when said testing means finds that a call has been initiated on said line.

8. In a telephone exchange system, a calling line, a plurality of subscribers' stations 10 on said line, a called line, message registers associated with said calling line and each individual to a subscriber's station, a line switch, a series of selective switches for completing conversational connections between 15 said calling line and said called line, a group of trunks extending between said line switch and said series of selective switches, means responsive to the removal of the receiver at a calling station for placing a discriminating test condition on the calling line and for 20 operating said line switch to seize an idle trunk in said group of trunks, testing means associated with said idle trunk and normally disconnected therefrom, said testing means 25 being responsive to said test conditions for selecting the message register individual to the calling station, means responsive to the seizure of said idle trunk and prior to the completion of the connection for locally operating said testing means, means for connecting 30 said testing means in its operated condition to the extended calling line to detect thereon the existence of said test condition or an unstandard condition, means for 35 checking the sensitiveness of said testing means after connection to the extended calling line, means effective after the successful establishment of a conversational connection for reoperating and reconnecting said test- 40 ing means in its operated condition to the extended calling line, and means effective after the release of a connection for operating the selected message register only when 45 said testing means finds that a call has been initiated on said line.

9. In a telephone exchange system, a calling line, two subscribers' stations on said line, a called line, trunks for extending said calling line to said called line, message reg- 50 isters associated with the incoming end of said calling line and each individual to a subscriber's station, means at one of said stations for placing a discriminating test potential on one of the conductors of the 55 calling line, a plurality of testing means each associated with one of said trunks and normally disconnected therefrom, means re- 60 sponsive to the automatic extension of the calling line to one of said trunks for energizing said testing means in a local circuit, means operative thereafter for applying said testing means in its operated condition to the extended calling line during the estab- 65 lishment of a connection and for reapplying said testing means to the extended calling

line subsequent to the restoration of the calling subscriber's receiver to its switchhook, means operated by said testing means upon its first application to the extended calling line and responding to said test potential 70 or an unstandard condition of said line for selecting one of said registers, and means operated by said testing means upon its second application to the extended calling line and responding to an unstandard condition 75 thereon for nullifying the selection of said register.

10. In a telephone exchange system, a calling line, a plurality of stations on said line, a called line, automatic switching mechanism 80 for extending said calling line to said called line to establish a conversational connection, message registers associated with said calling line and each individual to a station, means associated with said stations for placing a discriminating test condition on said calling line, testing means normally disconnected from the extended calling line, means for operating said testing means, means for applying said testing means in its operated condition to the extended calling line, means for again applying said testing means to the calling line, means responsive to the presence of a test condition for causing said testing means to select the message register 95 individual to the calling station, and means for preventing the second application of said testing means if no discriminating condition is encountered upon the first application. 100

11. In a telephone exchange system, a calling line, a plurality of subscribers' stations on said line, a called line, automatic switching mechanism for extending said calling line to said called line to establish a conversational connection, message registers associated with said calling line and each individual to a subscriber's station, means associated with said stations for placing discriminating test conditions on said calling line, a testing means normally disconnected from the extended calling line, means for operating said testing means, means for applying said testing means in its operated condition to the extended calling line, means for again applying said testing means to the calling line after the called subscriber answers, means responsive to the presence of a test condition for causing said testing means to select the message register individual to the calling station, and means for preventing the second application of said testing means if the called subscriber fails to answer. 110

In witness whereof, we hereunto subscribe 115
our names this 18th day of August A. D., 1924.

SAMUEL B. WILLIAMS.
EARL S. GIBSON.
